UNITED STATES PATENT OFFICE.

LEWIS J. BAZZONI, OF SWAMPSCOTT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

BUFFING-MACHINE.

1,274,366.

Specification of Letters Patent. Patented Aug. 6, 1918.

Application filed May 1, 1912. Serial No. 694,534.

To all whom it may concern:

Be it known that I, LEWIS J. BAZZONI, a citizen of the United States, residing at Swampscott, in the county of Essex and State of Massachusetts, have invented certain Improvements in Buffing-Machines, of which the following description, in connection with the accompanying drawings, is a specification, like reference characters on the drawings indicating like parts in the several figures.

This invention relates to abrading or polishing machines and is herein illustrated as embodied in a machine for buffing the bottoms of boots and shoes.

It is desirable that the bottom of a finished shoe shall be smooth and shall possess what is known in the trade as a "velvet finish". It is almost universally the custom to buff the bottoms of shoes by presenting them in succession to two rolls located side by side upon a rotating shaft, and, when the velvet finish referred to above is desired, to subject them to the further operation of a pneumatic pad which raises the nap and thereby produces the desired finish.

One object of the present invention is to produce the finish without the additional operation, and to this end there are provided two buffing tools arranged in proximity to each other whereby a shoe may be presented first to one and then to the other and means for causing the operative faces of said tools to travel in opposite directions. In the illustrative embodiment of the invention these tools take the form of abrasive belts having operative faces of comparatively coarse and comparatively fine abrasive material respectively, the shoe being presented first to the coarse, which removes the grain of the leather and accomplishes the first part of the smoothing operation, and then to the fine which completes the smoothing operation and at the same time raises the nap to give the desired finish.

In all buffing machines a large quantity of dust is produced which, for obvious reasons, must be removed as effectively as possible, and another feature of the invention consists in a plurality of abrasive belts arranged in proximity to each other and caused

to travel in opposite directions and an exhaust pipe having its receiving mouth located in proximity to adjacent portions of runs of the belts which are traveling toward each other.

It is desirable, for reasons which will presently be set forth, that means be provided for pressing upon or supporting the belt at selected localities, and other features of the invention consist of pressers which are caused, manually or automatically by the presentation of the shoe, to press upon the back of the belt and thereby support it in a selected locality.

These and other features of the invention including certain details of construction and combinations of parts will be described in connection with an illustrative machine and pointed out in the appended claims.

Referring now to the accompanying drawings:

Figure 1 is an elevation of a machine in which the present invention is embodied;

Fig. 2 is a perspective showing a portion of one of the abrasive belts, together with a shoe in the position which it occupies while the sole is being operated upon;

Fig. 3 is a rear elevation of a portion of one of the abrasive belts showing the position occupied by the presser to cause the belt to operate upon the depression in the sole at the base of the breast of the heel; and

Fig. 4 is a perspective of one of the abrasive belts, showing the position occupied by the support while the top-lift of the shoe is being buffed.

The base 1 of the machine is provided with a vertical arm 3 and two lateral arms 5 and 7. Pivotedly mounted upon the arm 3 are two swinging arms 9 and 11 yieldingly upheld by springs 13 and 15 and carrying at their outer ends pulleys 17 and 19. Co-operating with the pulley 17 are two smaller fixed pulleys 21 and 23 mounted as shown, while similar pulleys 25 and 27 co-operate with the pulley 19. An abrasive belt 29 passes around the pulleys 17, 21 and 23 and a similar belt 31 passes similarly around pulleys 19, 25 and 27, it being understood that one belt has an operating face of coarser

abrasive material than the other. Each belt thus has a horizontal run and two inclined or oblique runs. In the illustrative machine the pulleys 25, 27, 23, and 21 are in alignment so that the lower or operative runs of the abrasive belts are located in a common plane. This exact arrangement is, of course, not essential provided that the operative portions of the belts are adjacent so that a 5 shoe may conveniently be presented first to one and then to the other. In order to cause the abrasive belts to travel in opposite directions a main driving belt 30 transmits power from a driving pulley 33 on a suitably arranged power shaft 35 to a pulley 37 fast to a short shaft 39 carried by bearings in the upper part of the vertical arm 3; and from other pulleys on this shaft, one of which is shown at 41, the pulleys 19 and 21 10 are driven by means of open and crossed belts 43 and 45 respectively so that, as has been explained, the abrasive belts 29 and 31 travel in opposite directions.

It frequently happens that there is a depression in the sole of a shoe and this is particularly liable to occur adjacent the breast of the heel owing to the pressure exerted upon this portion of the sole during the heel-attaching operation. In order to provide 15 means for buffing such depressed areas, pressers 63 and 65 in the form of frusto-conical wheels are angularly movable about pivots 67 and 69 and are arranged to be depressed when desired by treadles 71 and 73 which 20 are connected by chains with the arms which carry the presser wheels. Springs 72 and 74 normally hold the presser wheels in 25 raised position. By using presser wheels of this particular shape it is possible, as will be 30 evident from an inspection of Fig. 3, to buff a depressed area in the shank close up to the 35 breast of the heel.

In buffing the toplift on a roll, as is commonly done, there is always a liability that 40 the edges of the toplift will be rounded thus giving to the finished shoe an undesirable appearance. If, in the present machine, the toplift were pressed against the unsupported belt a similar effect, although probably 45 of a less degree, might be produced. Accordingly, a flat faced support 75 is pivoted at 77 to a bracket 79 which is clamped to the arm 7. Fast to this support 75 is a heel rest 81 which extends along the front face of 50 the belt. The relative location of the pivot 77 and the support 75 is such that the face of the support is normally held lightly against the back of the belt by gravity. When now a heel of a shoe is placed upon 55 the rest, as illustrated in Fig. 4, a force is 60 said rest, as illustrated in Fig. 4, a force is thereby exerted to rotate the support about the pivot 77 and hence to press the support firmly against the back of the belt. Although only one such support has been

shown, it is obvious that another one similar to it may be mounted upon the other arm 5 if desired.

It has been stated above that one of the reasons for locating the lower runs of the belts as shown is to permit ready presentation of a shoe from one to the other. This arrangement, however, serves the further purpose of facilitating the removal of the dust produced by the buffing operation. An abrasive tool running at high velocity draws 75 with it in its movement a considerable amount of the dust produced. In the present machine, therefore, the dust will in a large part be drawn toward the center of the machine approximately in the direction of 80 the travel of the belts. In order to make use of this movement of the dust, an exhaust pipe 83 connected with a blower 85 is provided with a flaring mouth which conforms to the adjacent outlines of the pulleys 85 23 and 27, said mouth, for the purpose of making the draft more effective, having a partition 87 therein. The blower 85 may be driven in any convenient manner as, for example, by a belt 89 which passes over a pulley on the driving shaft 35.

In order to permit the abrasive belts 29 and 31 to be removed and replaced when desired, the arms 9 and 11 are connected with 95 treadles 91 and 93.

The operation of the device is as follows: Considering that the right hand belt 29 has a surface of coarser abrasive material than that of the belt 31 the shoe is first presented to the lower run of the belt 29 in the manner 100 illustrated in Fig. 2 and moved about by the operator until all portions in its surface have been thoroughly operated upon. If there are depressions in the sole, the operator depresses the treadle 73 so as to bring the 105 presser wheel 63 down upon the back of the belt and thereby force it into such depressions. During this part of the operation the grain of the leather is removed but the fiber or nap is all laid in one direction. The sole 110 is then presented to the left hand belt which completes the smoothing of the surface of the sole and at the same time raises the nap to produce a velvet finish. During this time the dust produced by the operation of the 115 belt is carried along to the mouth of the exhaust pipe 83 through which it is drawn by the action of the blower. In order to buff the toplift of a heel the shoe is presented to the belt or belts in the manner 120 illustrated in Fig. 4, and, if necessary, a slight downward pressure is exerted upon the shoe so as to hold the support rigidly in place against the back of the belt.

Although the invention has been set forth 125 in connection with a particular machine, it should be understood that the invention is not limited in the scope of its application

to the particular machine shown and described.

Having thus described my invention, what I claim as new and desire to secure by Letters Patent of the United States is:—

1. A machine of the class described having, in combination, a set of pulleys, a belt running around the pulleys of said set, a second set of pulleys having their ends in substantially the same plane as those of the first set, a second belt running around the pulleys of the second set, means for operating one pulley of each set to cause the operative runs of the belts to travel toward each other, pressers normally held out of contact with the back of the operative runs of said belts, said pressers being shaped to enter the angle between the sole of a shoe and the breast of the heel, and treadle operated means for moving said pressers into contact with the backs of said operative runs, there being a free and unobstructed space beneath said operative runs to permit manual presentation of a shoe.

2. A machine of the class described having, in combination, a plurality of buffing belts arranged in proximity to each other in position to permit a shoe to be presented manually first to the operative run of one and then to the operative run of the other, means for causing the operative runs of said belts to travel toward each other and an exhaust pipe common to the two belts and having its receiving mouth located in proximity to adjacent portions of the runs of the belts which are traveling toward each other.

3. A machine of the class described having, in combination, a plurality of buffing belts arranged in proximity to each other in position to permit a shoe to be presented manually first to the operative run of one and then to the operative run of the other, means for causing the operative runs of said belts to travel toward each other, and a frusto-conical rotary member movable at will into and out of contact with the back of the operative run of one of said belts.

4. A machine of the class described having, in combination, a plurality of buffing belts having approximately horizontal operative runs which are normally straight, there being a free and unobstructed space beneath said runs to permit manual presentation of a shoe first to one belt and then to the other, means for causing said operative runs to travel toward each other, a presser located adjacent the back of each belt at the operative run thereof and normally out of contact therewith, and treadle actuated means for causing either presser to contact instantly with the back of the respective belt and thereby force said belt downwardly at the point of contact.

5. A machine of the class described hav-

ing, in combination, a belt having an inclined run, a combined belt supporting and heel supporting member and a pivot connecting said member with the frame of the machine.

6. A machine of the class described having, in combination, a belt having an inclined run, a flat faced member pivoted to the frame of the machine and arranged to be held against the back of said belt by gravity, said member being provided with a heel supporting portion extending partially across the face of said belt.

7. A machine of the class described having, in combination, a belt having an approximately horizontal operative run, arranged to permit presentation thereto of the sole of a shoe, and an oblique run, means for actuating said belt, and a member having a flat face arranged to contact with the back of a portion of said oblique run and a portion for supporting the heel of a shoe with the toplift in contact with the face of said oblique run.

8. A machine of the class described having, in combination, two sets of pulleys arranged in the form of triangles with their bases approximately in alinement, belts arranged to travel one around each set of pulleys, means for causing the operative runs of said belts to travel in opposite directions, yielding means for supporting one pulley of each set whereby the belts are maintained taut, and treadle actuated means for moving said yieldingly supported pulleys in opposition to said yielding means.

9. A machine of the class described having in combination, a set of pulleys, a belt running around the pulleys of said set, a second set of pulleys having their ends located in substantially the same plane as those of the first set, means for rotating one pulley of each set in a direction to cause the operative runs of the belts to travel toward each other, said operative runs being approximately horizontal and terminating in upwardly extending runs, a pulley of one set being located in proximity to a pulley of the other set at the points at which the operative runs terminate, and an exhaust hood extending up between said last-named pulleys.

10. A machine of the class described having, in combination, a set of pulleys, an abrasive belt running around the pulleys of said set, a second set of pulleys having their ends in substantially the same plane as the first set, an abrasive belt running around the pulleys of the second set, said belt having an operative face of a different degree of fineness from that of the first mentioned belt, means to cause the operative runs of said belts to travel toward each other, pressers normally held out of contact with the

back of the operative runs of said belts, said
pressers being shaped to enter the angle be-
tween the sole of a shoe and the breast of a
heel, and manually operative means for
5 moving said pressers into contact with the
backs of said belts.

In testimony whereof I have signed my

name to this specification in the presence of
two subscribing witnesses.
